UNITED STATES PATENT OFFICE.

JOHN GRAHAM, OF NEW YORK, N. Y., ASSIGNOR TO HOLBROOK COMPANY, OF NEW YORK, N. Y., A CORPORATION OF NEW YORK.

DESIGN FOR A VEHICLE BODY.

60,137.

Specification for Design.

Patented Jan. 3, 1922.

Application filed September 15, 1920. Serial No. 410,571. Term of patent 14 years.

To all whom it may concern:

Be it known that I, JOHN GRAHAM, a citizen of the United States, residing at New York, New York County, and New York State, have invented a new, original, and ornamental Design for Vehicle Bodies, of which the following is a specification, reference being had to the accompanying drawings, forming part thereof.

Fig. 1 is a side elevation of a vehicle body showing my new design.

Fig. 2 is a rear view of the same.

Fig. 3 is a front view of the body.

The design particularly embraces the sunken panel or depressed molding *a*.

I claim:

The ornamental design for a vehicle body, as shown.

In testimony whereof, I have signed my name to this specification in the presence of a subscribing witness, this third day of September, 1920.

JOHN GRAHAM.

Witness:

CHARLES T. BARTHEL.
